By Ward & Cameron
Albion,

UNITED STATES PATENT OFFICE.

JAMES F. MCELROY, OF ALBANY, NEW YORK, ASSIGNOR TO CONSOLIDATED CAR-HEATING CO., OF SAME PLACE.

STEAM-HOSE COUPLING.

SPECIFICATION forming part of Letters Patent No. 669,960, dated March 12, 1901.

Application filed December 27, 1900. Serial No. 41,244. (No model.)

To all whom it may concern:

Be it known that I, JAMES F. MCELROY, a citizen of the United States of America, and a resident of the city of Albany, State of New York, have invented certain new and useful Improvements in Steam-Hose Couplers, of which the following is a specification.

My invention relates to steam-couplers particularly adapted for connecting steam-hose between cars in railway-car-heating apparatus; and the object of my invention is to provide a steam-coupler composed of two like halves adapted to be fastened together and to be broken automatically by the disengagement of the adjoining cars, each half of said coupler being provided with a hinged gasket-holder. I attain this object by means of the mechanism illustrated in the accompanying drawings, in which—

Figure 1 is a plan; Fig. 2, an elevation; Fig. 3, a perspective view; Fig. 4, an elevation showing the two parts of the couplers joined.

Similar letters refer to similar parts throughout the several views.

Each half of the coupler consists of a casting A, preferably provided with an upturned nozzle B and a wing C, which wing projects beyond the face of the coupler and which carries a locking-flange D, adapted to engage with a lug E on the opposite side of the adjoining coupler-head. The mode of fastening the two parts of the couplers together, as shown in the drawings, is substantially that of the well-known Sewall coupler, and I do not limit myself to any particular means for accomplishing this result, but show this as one of the ways in which the locking together of the two parts may be accomplished. For the purpose of retaining the gasket in posi-

tion and to allow for the removal of an old gasket and the insertion of a new I place the plate F, containing an opening for a gasket G therein, which plate is hinged to the casting A by means of the bolt H and lugs h or in any suitable manner. At the side of the plate F, I preferably attach or form integral therewith a lug f, adapted to fit within a suitable opening in the wing C adjacent to the face of the casting A. I preferably place on the

plate F, near the lower portion thereof, a rib 50 K, extending about half-way across the face of the plate, and cut a groove k, corresponding to said rib, in the face of the plate F from the end of the rib K to the edge of the plate F, as shown in Fig. 3, which groove k is adapted to receive the rib K on the adjoining half of the coupler when they are brought together.

On the wing C, I preferably pivot a catch L, which may be brought in contact with the lug f when the plate F is closed, which will hold the plate F and gasket G securely in position. Gasket G is placed within the plate F when the plate is opened, portion g of the gasket G protruding through the opening in the plate F, the sides g of the gasket G in the rear of the plate F extending beyond the opening in contact with the rear surface of the plate. When the plate is closed and locked by means of the catch L coming in contact with the lug f, the gasket is held positively in position and can be readily removed by opening the plate and a new one can be quickly inserted.

I do not limit myself to the use of the rib K and groove k on the face of the plate F nor to the manner of securing the plate by means of the catch L and lug f nor to a hinged construction, as shown and described.

What I claim as my invention, and desire to secure by Letters Patent, is—

1. In a steam-hose coupler consisting of two like halves or portions, each of which consists of a casting provided with a projecting locking-wing on one side; a locking-lug on the opposite side; a gasket-holder; a means for hinging said gasket-holder to said casting; with a means for locking said gasket-holder in position.

2. In a steam-hose coupler, two like halves or portions; each half consisting of a casting; a means for locking the two halves together; a gasket-holder; a means for hinging said gasket-holder to the casting; a rib on said gasket-holder extending across the lower portion thereof; a groove cut in the face of said gasket-holder from the end of said rib to the edge of said holder; with a means for locking said gasket-holder.

3. In a steam-hose coupler consisting of two like halves or portions, a casting; a means for uniting the two portions of the casting together; a gasket-holder; a means for hinging said gasket-holder to the casting; a means for locking said gasket-holder in position, substantially as described.

Signed at Albany, New York, this 25th day of December, 1900.

JAMES F. McELROY.
